UNITED STATES PATENT OFFICE.

ROBERT C. ABT, OF CHICAGO, ILLINOIS.

NUTCRACKER.

1,289,351.

Specification of Letters Patent. Patented Dec. 31, 1918.

Application filed November 9, 1916. Serial No. 130,412.

To all whom it may concern:

Be it known that I, ROBERT C. ABT, a citizen of the United States, residing at Chicago, in the county of Cook and State of Illinois, have invented certain new and useful Improvements in Nutcrackers, of which the following is a description.

My invention belongs to that general class of devices known as nut crackers, and relates particularly to a simple and convenient device to be used for cracking or crushing the shells of the nuts. The invention has among its objects the production of a device of the kind described that is simple, convenient, durable, efficient, ornamental, attractive and satisfactory. It has particularly as an object the production of a convenient nut cracking device having a suitable and ornamental base for carrying the cracking device, which base may be supported on a table or like support, or held on the knees or in the lap, the same being preferably formed to hold the nuts to be cracked as well as the cracked nuts, if desired, and the fragments of the shells. The invention has further among its objects the production of a device suitable for all sizes of nuts, as well as nuts having extremely tough shells or thin shells that may be more easily fractured. Many other objects and advantages of the construction herein shown and described will be obvious from the disclosure herein made.

To this end my invention consists in the novel construction, arrangement and combination of parts herein shown and described, and more particularly pointed out in the claims.

In the drawings, wherein like reference characters indicate like or corresponding parts,

Figure 1 is a sectional view of one form of the device taken substantially on line 1-1 of Fig. 2;

Fig. 2 is a sectional view taken substantially on line 2-2 of Fig. 1;

Fig. 3 is a sectional view taken substantially on line 3-3 of Fig. 2, and

Fig. 4 is a sectional view similar to Fig. 1, illustrating a slight modification.

Referring to the drawings, 1 represents what may be termed a base, which is preferably recessed or formed as at 2 to substantially constitute a receptacle, 3 being the rim of the receptacle extending thereabout. The base on the interior at the center is

formed with a face 4 of the desired size arranged to support and brace the cracker frame, as hereafter described. The base is also provided with a hole or opening 5 extending therethrough at the center with a shoulder 6 arranged at the lower end, the base being substantially countersunk at the under side to form the shoulder 6.

The cracker frame consists of the upright 8, having a base 9 arranged to seat on face 4, and provided with a lug 10 of a size to extend into the opening or hole 5, and preferably lie substantially flush at the end with the shoulder 6. In the construction shown the under side of the base is formed with one or more lugs or ribs 11 arranged to project into recesses in the base 1, so that the frame is not rotatable on the base. The frame shown is formed with a nut cracking or crushing face 12 at the upper side of its base 9, and at the top the same is provided with an extension 13 formed with an opening and internally threaded thereat. It will be noted that the part 13 is above the base 9, the part 8 being substantially an offset web, which surrounds the base on a plurality of sides. The frame may be secured to the base 1 in any desired manner. As shown, bolt 14 extends through the part 10 and engages a nut 15. A washer 16 may be arranged as shown, the same being of sufficient size to overlie the base and engage at the shoulder 6. Of course if the nut 15 is of sufficient size the washer 16 may be omitted.

Carried by the frame 8 is a threaded rod or bar 17, which projects through the extension 13 of the frame and rotatably engages with the thread formed therein. The upper end of the threaded rod 17 is provided with a cross-bar or operating handle 18, or the equivalent for the purpose. The lower end of rod 17 or the end adjacent the face 12, may be formed as at 19, or in an equivalent manner, so that when a nut is placed substantially as indicated at 20 (dotted lines) the same will be engaged by the end 19 and by the face 12. As before mentioned, the part 8 is substantially offset, and forms a guard open at one side about a portion of the rod 17. If desired, a guard 21 may be arranged at the open side of the part 8, as shown, the same adding somewhat to the appearance, and if sufficiently extended, the same will prevent portions of the nut shells or small splinters flying and dropping outside of the rim of the base 1.

limiting myself to the exact form, construction, arrangement or combination of parts herein shown and described or uses mentioned.

60

What I claim as new and desire to secure by Letters Patent is:—

1. A nut cracker comprising a base portion having an upstanding part at one side thereof and carrying adjustable nut cracking means adapted to oppose the base portion, said upstanding part being offset to aline said adjustable nut cracking means with said base portion, the side edges of said upstanding portion being turned outwardly at points located inwardly of and above the base portion to provide a widened flaring open side portion to accommodate the fingers of the operator and facilitate the introduction and removal of a nut.

65

70

2. A nut cracker comprising a base portion having an upstanding part offset to overhang the base portion and carrying an adjustable nut cracking means alined with the base portion, the edges of the base portion opposite the said upstanding part being free to provide an opening thereabove and at its sides, and an outwardly and downwardly curved elongated depending apron-like guard extending downwardly alongside the said adjustable nut cracking means and terminating above the relatively free edge of the base portion to constitute a hood for the purpose described.

75

80

3. A nut cracker comprising a base portion having an upstanding part offset to overhang the base portion and carrying an adjustable nut cracking means alined with the base portion, the edges of the base portion opposite said upstanding means being free to provide an opening thereabove and at its sides, a depending apron-like guard extending a substantial distance downwardly alongside the said adjustable nut cracking means and terminating above the 85 relatively free edges of the base, and means for securing said apron-like guard for separate opening movement outwardly to enlarge the said opening through which the nut may be introduced or withdrawn.

ROY W. HILL,
CHARLES I. COBB.

In using the device the rod 17 is turned so as to raise the end 19. The nut may then be placed under the same and the rod 17 turned so as to engage and crush the nut.

5 The base 1 is not only suitable to carry the nuts to be cracked, but it may also carry the cracked nuts, and particularly the shells resulting from cracking or crushing of the nuts. The same is particularly convenient, 10 as it catches the fragments of cracked shells and permits the device to be held on the lap without danger of having shells drop on the floor. It also permits the application of greater pressure on the nut, as owing to the 15 size of the same, it may be easily gripped with the hand and a considerable leverage obtained, when the handle 18 is turned. Where the base 1 is omitted I find that there is a tendency for the frame 8 to slip and 20 turn in the hand. Owing to the particular construction shown, however, the frame is rigidly and non-rotatably held by the base 1, and considerable power may be applied to the nut by the rod. Owing to the im- 25 proved method of fastening the two parts together, there is no danger of the base or bowl 1 being cracked or broken, nor for the cracker to become loose and wabble thereon. This is particularly important where the 30 bowl is made of wood, papier mâché or like material, of light weight and easily fractured.

The construction shown in Fig. 4 is very similar, 1 being the base or bowl carrying the frame 8', which is secured in place by the screw 14' and washer 16', and carries the rod 17' having a head 18', which rod extends through the part 10' of the frame. I have shown the part 10' threaded into the bowl or base. In this case I have shown a pivoted baffle or guard 21', which is pivotally secured at 22 to the frame. This may be dropped down while the nut is being cracked, the same preventing any fragments 45 of the shell of the nut flying out over the edge of the bowl or base. The same also adds to the appearance of the device. While the rim of the base is ordinarily made of the height indicated in Fig. 1 in the full 50 lines, it may, if desired, be made higher, as indicated at 23 in the dotted lines.

Having thus described my invention, it is obvious that various immaterial modifications may be made in the same without departing from the spirit of my invention; 55 hence I do not wish to be understood as
